UNITED STATES PATENT OFFICE.

REX V. SNYDER, OF EAST ORANGE, NEW JERSEY, ASSIGNOR TO THE AMERICAN THREAD COMPANY, OF NEW YORK, N. Y., A CORPORATION OF NEW JERSEY.

WOUND BOBBIN.

Application filed February 3, 1926. Serial No. 85,647.

My invention relates to new and improved bobbins for sewing machines and the like and has for its object to provide a wound bobbin having a tubular core and end pieces secured thereto by overlapping portions of the core secured by adhesive.

The following is a description of an embodiment of my invention, reference being had to the accompanying drawings, in which,

Figure 1 shows the elements of the bobbin assembled and in position to be compressed;

Fig. 2 shows a central section of the bobbin in completed form;

Fig. 3 shows an end view of the same.

Referring more particularly to the drawings, Fig. 1, 2' is a core upon which is a mass of thread 4' universally wound. 6 are end pieces of cardboard or other suitable material having perforations at their center adapted to fit over the ends of the core. These end pieces have concavo-convex portions 8, and a flattened zone 10 surrounding the perforations, the inner concave surface of the disk conforming approximately to the normal curvature of the thread mass when first wound. The ends of the tubular core are slit as shown at 12 and in the completed bobbin the resulting projections 14 are bent over the flattened zone and secured thereto by adhesive. This bending is done by suitable plungers which not only bent over the projections 14 so as to form the core 2 of Fig. 2 but compress the mass of thread as shown at 4, Fig. 2, so as to make its ends conform closely to the inner surfaces of the end pieces, as shown in Fig. 2. The normal curvature of the concavo-convex portions of the disk is slightly sharper than the normal curvature of the end pieces of the uncompressed wound mass with the result that the pieces are under a spring tension and exert a pressure upon the mass which

tends to hold the end pieces in contact with the outer edges of the mass so as to prevent 45 a formation of spaces into which a thread being unwound is liable to fall.

The concavo-convex portions of the disk result in forming a re-entrant portion 16 in which the bent over portions 14 are contained so as to be removed from contact with the walls of the bobbin holder, so that the friction is substantially on the higher external surfaces of the concavo-convex portions 50 of the disks.

In this way a bobbin is produced in which the end pieces are securely held by adhesive in conjunction with the bent over portions 55 of the core.

As will be evident to those skilled in the art, my invention permits various modifications without departing from the spirit thereof or the scope of the appended claims.

What I claim is:

1. A wound bobbin comprising a core, a 60 mass of thread wound universally thereon, perforated end pieces surrounding said core and adjacent to the ends of said mass, the ends of the core being slit and bent over the outer surfaces of said end pieces, said end 65 pieces having central reentrant portions containing the bent over slit ends of the core.

2. A wound bobbin comprising a core, a 70 mass of thread wound universally thereon, perforated end pieces surrounding said core and adjacent to the ends of said mass, the ends of the core being slit and bent over the outer surfaces of said end pieces, and secured thereto by adhesive, said end pieces 75 having central reentrant portions containing 80 the bent over slit ends of the core.

In testimony whereof, I have signed my name to this specification this first day of February, 1926.

REX V. SNYDER.
